(57) **CLAIM**

The ornamental design for a display screen with a graphical user interface, as shown and described.

DESCRIPTION

The file of this patent contains at least one drawing executed in color. Copies of this patent with color drawing(s) will be provided by the Office upon request and payment of the necessary fee.

1. Graphical user interfaces for display screens

The figure is a front view of a display screen with a graphical user interface showing our new design.

The broken lines showing a display screen form no part of the claimed design.
